APPARATUS FOR CLEANING FABRICS AND
THE LIKE

Abraham Traube, Brooklyn, N. Y.

Application May 14, 1937, Serial No. 142,566

4 Claims. (Cl. 15—105)

This invention relates to apparatus for use in cleaning fabric and the like and more particularly to apparatus comprising means for supplying cleaning fluid to the fabric to be cleaned and for scraping or rubbing the fabric to remove spots, such as hard paint spots, stains, etc. The apparatus comprises a hand device such as used in dry-cleaning establishments in what is known as "spot-cleaning" for the removal of paint spots and the like.

One object of the invention is to provide apparatus comprising a hand device including an improved scraping implement and means for supplying cleaning fluid to the scraping edge thereof. A further object is to provide a stationary container in combination with a hand-operated scraping device and a flexible connection from the said container to said device. A still further object is to provide a hand device comprising a scraper, a brush, and a valve control for regulating a supply of cleaning fluid from a remote container.

With these and other objects in view, the invention consists in the novel constructions and arrangements of parts hereinafter described, illustrated in the accompanying drawings, and particularly pointed out in the appended claims, it being understood that various changes in the forms, and minor details may be made without departing from the spirit of the invention or sacrificing any of the advantages thereof.

In the drawings:

Fig. 1 is a side view of the apparatus with the hand device shown in plan view;

Fig. 2 is an enlarged view of the hand device shown partly in section;

Figs. 3 and 4 are further enlarged views showing the hand device in use for scraping and for brushing respectively;

Fig. 5 is a view of the device looking in the direction of the arrow 5 in Fig. 4;

Fig. 6 is an inverted plan view of the device;

Fig. 7 is a view corresponding to Fig. 1 but showing a modified form of the complete apparatus and with the hand device shown partly in section; and

Fig. 8 is a similar view showing another modification.

The hand device shown on the drawings comprises a hollow handle 10 carrying a curved nozzle member 11 having a scraping edge 12 and having a discharge outlet 13 for the cleaning fluid. The device is also formed with a suitably inclined member 14 for engagement by the palm 50 of the hand when the device is in use, as shown at Figs. 3 and 4. A socket member 15 is also provided for the reception of a flat faced removable brush 16, and the arrangement is such that when the scraping edge 12 is in engagement with the 55 surface 17 being cleaned the brush 16 is clear

of the said surface, and when the brush is in use as shown at Fig. 4 the scraper 12 is raised from the surface 17. The construction of the device is such that slight tilting or rocking movement of the hand very conveniently brings either the 5 scraper or the brush into its operative position, so that scraping and brushing operations may be conveniently performed without loss of time or energy in changing from one operation to another. The device is also provided with a leather 10 or other like strap 18 which passes over the back 15 of the hand of the user when the device is in operation and the arrangement provides a convenient grip to facilitate the scraping and brushing operations and the manipulation of the fluid control 15 as hereinafter described.

In the form of the apparatus shown in Fig. 1 the cleaning spirit or other volatile fluid as commonly used for softening paint spots and the like is carried in an elevated container 19 which is inverted and supported from a yoke 20 so that the fluid may pass by gravity through a restricted outlet 21 and through a flexible tube 22 to the hollow member 10 of the hand device. The container 19 is also provided with an internal tube 24 extending upwardly to a point above the level of the fluid when the container is in its inverted position, as shown in Fig. 1, and the external air inlet end of this member 24 is provided with a suitable regulating device 23 whereby the admission of air may be regulated to suit requirements.

As shown at Fig. 2 of the drawings, the hand device is also provided with a thumb-button 25 which is secured on the outer end of a stem 26 connected to a valve 27 which is held on its seat by a spring 28, and when the button 25 is pressed inwardly by the thumb the valve 27 is raised from its seat against the action of the spring 28 and cleaning fluid is permitted to pass from the bore 29 in the member 10 to a bore 30 in the nozzle 11, so that cleaning fluid is delivered to the surface 17 being cleaned. As is clearly shown at Figs. 3 and 4, the thumb conveniently rests upon the bottom 25 so that the supply of fluid to the cleaning surface is always under complete and convenient control.

The modified form of apparatus shown at Fig. 7 comprises a fluid-containing tank 31 which is preferably located at a lower level than the hand device when in use. This container 31 is provided with an internal dependent tube 32 extending to a point near the bottom of the container and communicating with a flexible tube 33 by means of which fluid may be supplied to a bore 34 in the hand device, which latter is also formed with a cylindrical cavity 35 containing a piston 36 connected to a stem 37 having a button 38 on its outer end, and having a spring 39 in compression between the said button 38 and the

device. Between the said bore 34 and the cylindrical cavity 35 a non-return valve 40 is provided, and a passage 41 leads from the cavity 35 to the nozzle 11 and has a non-return valve 42 therein. The said valves 40 and 42 being provided with springs 43, 44 respectively, so that reciprocation of the piston 36 by means of the button 38 first forces air and then fluid outwardly through the nozzle 11 and causes a flow of cleaning fluid from the container 31 through the tube 32 and the flexible tube 33, and by way of the valves 40 and 42 to the nozzle 11. The container 31 may thus be located at a level lower than the working position of the hand device, and while air is admitted to the container 31 through a controlled air inlet 45, fluid may be raised by the pumping action above referred to so as to deliver a proper quantity as and when required to the scraping edge of the nozzle 11. As there is no gravity feed from the container 31, according to this arrangement, the possibility of leakage of the highly volatile and inflammable cleaning fluid is effectively prevented.

In the modified form of the apparatus shown at Fig. 8, a sealed tank 46 contains the cleaning liquid, and a flexible air tube 47 is connected to a cap 48 on the container and to a bore 49 in the hand device which latter is also formed with a cylindrical cavity 50 communicating with the said bore 49 and having a cup-leather piston 51 operated by a stem 52 having a thumb button 53 and a return spring 54. The bore 49 is provided with a non-return valve 55 having a spring 56 and as the piston 51 is reciprocated by means of a button 53 air is drawn inwardly through a vent 57, raises the valve 55 and passes through the air tube 47 so that pressure is exerted in the container 46 above the level of the cleaning fluid which is thus caused to pass upwardly through an internal pipe 58 which extends downwardly from the said cap 48 to a point close to the bottom of the container. From the pipe 58 the fluid is forced through a flexible pipe 59 to a bore 60 in the hand device, so that fluid is thus supplied by air pressure to the nozzle 11.

The nozzle 11 and brush 16 are preferably attached to the hand device in such manner that they may be conveniently removed in order to permit replacement as these parts become worn out, and as shown particularly at Fig. 6 the nozzle 11 may be provided with a set screw 61 adapted to contact with a hollow nipple 62 upon which the nozzle may be fitted. The brush 16 is preferably fitted into a tapered socket 15 so that it may be readily and conveniently removed for replacement.

Although the drawings and the above specification disclose the best modes in which I have contemplated embodying my invention, I desire to be in no way limited to the details of such disclosure, for in the further practical application of my invention many changes in forms and constructions may be made as circumstances require or experience suggests without departing from the spirit of the invention within the scope of the appended claims.

What I claim is:

1. A portable hand operated device for use in "spot-cleaning" fabrics comprising a body part, a nozzle projecting from the body part for conveying cleaning fluid to the surface being cleaned, a scraping edge on the end of the nozzle, a re-

stricted fluid outlet at the said edge, a flat-faced brush so secured on the underside of the body part that its flat face engages the surface being cleaned only when the said scraping edge is raised slightly from the said surface, and so that the said face is disposed at a slight angle to the said surface when the latter is engaged by the scraping edge, and a flexible strap connected at its ends to said body and holding the latter in close engagement with the hand.

2. A portable hand operated device for use in "spot-cleaning" fabrics comprising a hollow body, a curved nozzle projecting outwardly and downwardly from the body, a rigid scraping edge on the nozzle, a restricted fluid outlet at the said edge, a hollow nipple on the body for removably receiving the nozzle, a socket in the underside of the body, a flat-faced brush removably secured in the socket in such a position that its flat face engages the surface being cleaned only when the scraping edge is slightly raised from the said surface, and that the said face is disposed at a slight angle to the said surface when the latter is engaged by the scraping edge, and a flexible strap attached to the device and adapted to hold the device in close contact with the hand so that the fingers may press upon the said curved nozzle.

3. A portable hand-operated device for use in "spot-cleaning" fabrics by alternately brushing and scraping, which comprises a rigid body member having a protuberance for engagement with the palm of the hand, a flexible strap secured at both ends to said body and adapted to extend over the back of the hand, an outwardly and downwardly extending portion on the side of the body opposite to said protuberance whereby the fingers of the hand may rest—and exert pressure upon—said extension while the hand is held in close contact with the device by said strap, a flat-faced brush secured to the underside of the body, and a scraping edge on the lower extremity of said extension and located in close proximity to the plane of the working face of said brush, so that a slight angular tilting movement is sufficient to change the device from the brushing to the scraping operation, means for directing cleaning fluid to the scraping edge, and a fluid-control member conveniently located for actuation by the hand without removal of the hand from the brushing and scraping positions.

4. A portable hand-operated device for use in "spot-cleaning" fabrics, comprising a brush and a scraper located in close proximity to the plane of the working face of the brush but spaced from the brush itself, a body part having an inclined member for engagement with the palm of the hand and a curved depending member carrying the scraper and shaped for engagement by the fingers, means for supplying cleaning fluid to the scraper, a control member for said fluid, and a flexible strap connected to the device and holding same in close engagement with the palm of the hand and with the fingers whereby the said fluid-control device may be conveniently actuated without releasing the grip and while pressure is being exerted by the fingers upon the scraper, a slight tilting movement of the device being sufficient to change from one to the other of the brushing and scraping positions.

ABRAHAM TRAUBE.
